INTERRUPTER

Coleman B. Moore, Carroll Park, Pa., assignor to
 The Brown Instrument Company, Philadelphia,
 Pa., a corporation of Pennsylvania

Application September 24, 1938, Serial No. 231,465

7 Claims. (Cl. 200—32)

The present invention relates to interrupters and more particularly to an interrupter which is used to periodically open and close a switch.

It is an object of my invention to provide a device which is adapted to periodically open and close a switch for a predetermined percentage of a cycle of fixed time length. It is a further object of my invention to provide an interrupter which may be adjusted to provide for opening and closing of a switch for various lengths of time as may be desired.

The various features of novelty which characterize my invention are pointed out with particularity in the claims annexed to and forming a part of this specification. For a better understanding of the invention, however, its advantages and specific objects obtained with the use, reference should be had to the accompanying drawing and descriptive matter in which I have illustrated and described a preferred embodiment of the invention.

In the drawing:

Fig. 1 is a front view of an interrupter with its cover removed, and

Fig. 2 is a section taken on line 2—2 of Fig. 1.

The apparatus of my invention is mounted in a casing consisting of a base member 1 provided with upstanding side walls 2 that receive a cover member 3. The outer edges of the cover member 3 telescopically over the side walls 2 and may be attached thereto in any suitable manner. The cover is, however, movable to provide access to the apparatus contained within. Attached to and projecting forwardly from the base member 1 are four studs 4 upon two of which in the upper left corner of the casing is mounted a plate 5 which serves as a terminal block for the terminals 6. The plate 5 is supported on the studs by means of screws 7 extending through the plate and threaded into the studs.

In a similar manner a plate 8 is supported from the other two studs by screws 9 extending through the openings in the plate and being threaded into the studs. This plate supports the interrupter mechanism which is now to be described.

Mounted on the base plate 1 is constant speed electric motor 10 which has attached to its shaft in front of the plate 8 a gear 11 that meshes with another gear 12 journaled for rotation around a shaft 13. The shaft 13 is in turn mounted for oscillating movement in the plate 8 and a journal 14 projection from the base. Also pivotally mounted on the shaft 13 is a cross piece 15, behind plate 8, and a crosspiece 16, in front of plate 8, the latter of which has a downwardly extending

projection that supports a cam roller 17. The members 15 and 16 are joined to form a rigid assembly by rods 18 and 19 which extend respectively through arcuate openings 20 and 21 in the plate 8, the entire assembly being biased in a counter-clockwise direction in Fig. 1, until rod 18 engages the lower end of opening 20, by a spring 22 coiled around the shaft 13. Attached to the cross piece 15, below the shaft 13, and extending forwardly therefrom, are two brackets 23 that are adapted to support a switch 24. This switch may be of any commercial form and of a capacity suitable for the application for which the interrupter is being used.

Attached to the front ends of shaft 13 is a lever member 25 that has mounted on it for rotation a gear 26, in mesh with gear 12, and a generally heart shaped cam 27. The lower edge of this lever is arcuate in shape with the shaft 13 as a center and is formed as a gear sector 28 with its teeth in mesh with a gear 29 on a shaft 30. This latter shaft is journaled in the plate 8 and extends forwardly through the cover 3. Removably fastened to the shaft 13 in front of the cover 3 is a combined pointer and handle 31 that cooperates with a scale 32 on the front of the cover.

The cam 27 is rotated through gears 11, 12 and 26 from the motor 10 and is adapted, in its rotation to engage the roller 17 on cross piece 16 to tilt the switch 24. By rotating the handle 31 the lever member 25 may be moved to bring the cam nearer to or further from the roller 17 and thereby cause the cam to be in engagement with the roller for longer or shorter time during each revolution thereof.

In the operation of the device the spring 22 biases the switch 24 into either its open or closed position, preferably the latter, and the rest of this description will be based on that assumption. The cam 27 is rotated at a constant speed by the motor 10 and during each rotation engages the roller 17 to tilt the switch 24 into a clockwise direction to its open position. The nearer the cam is to roller 17 the longer the switch 24 will be held open for each revolution of the cam. This time that the switch is open or closed may also be determined in percentages of a revolution of the cam if desired. By rotating handle 31 in a clockwise direction the cam will be moved to the right and it will be in engagement with the roller to hold the switch open a shorter length of time.

The gear sector 28 is long enough so that the cam may be moved from a position at the left in which it will hold the switch open for its full

revolution to a position at the right in which it will not engage roller 17, and will, therefore, permit the switch to stay closed while the cam idly revolves. Stops 33 and 34 are provided 5 projecting from plate 8 to limit the movement of the lever member in either direction. The scale 32 is provided with marks on it that are adapted to cooperate with the pointed end of handle 31 to indicate the position of the cam. The marks on 10 the scale may either be in terms of time or in terms of percentage of a revolution of the cam 24 that the switch is open or closed.

There is diagrammatically shown in Fig. 1, one 15 use of the interrupter. In that figure there is shown an electric furnace 35 that has a heating coil 36 which is connected at one end to one side of the line and at the other end by means of conductors 37 and 38 to switch 24 and from there by conductors 39 and 40 to the other side of the 20 line. In operation, as the switch 24 of the interrupter is opened and closed the current flow through the heating coil 36 is maintained at an average value dependent upon the time the switch is closed and, therefore, the temperature of 25 the furnace is kept at a corresponding value. By turning handle 31 the cam 27 may be adjusted to let the switch remain closed a longer or a shorter time and thereby raise or lower the temperature of the furnace. In a similar manner, by providing 30 a switch of the proper size the interrupter of my invention may be used in any application where it is desired to periodically open and close a circuit.

As will be obvious from the above detailed 35 description I have invented an interrupter of practical form that is easy to assemble and adjust, and one that will not easily get out of order.

While in accordance with the provisions of the statutes, I have illustrated and described the best 40 form of my invention now known to me, it will be apparent to those skilled in the art that changes may be made in the form of the apparatus disclosed without departing from the spirit of my invention as set forth in the ap- 45 pended claims, and that certain features of my invention may sometimes be used to advantage without a corresponding use of other features.

Having now described my invention, what I 50 claim as new and desire to secure by Letters Patent is:

1. A timer comprising in combination with a switch, a tilttable support therefor, a projection on said support, a cam adapted to engage said projection, means to rotate said cam, and means to shift said cam through an arc concentric with the path of movement of said projection.
2. In a periodically operated switch, a rockable support therefor, means to bias said support in one direction and means to limit the movement 55 of said support in said direction, a pivoted member, a constantly rotating cam mounted on said

member and adapted to engage said support during a variable portion of its rotation to tilt said switch against the force of said biasing means, drive means for said cam and means to move said lever while said cam is being rotated by said drive means to move said cam member, toward and away from said support, whereby the support will be engaged thereby for a longer or shorter time during each rotation of the cam.

3. In an adjustable interrupter, a switch, a 10 rockable support therefor, said support having a projection extending therefrom, a pivoted lever, a cam rotatable on said lever and adapted to engage said projection during its rotation, means to rotate said cam whereby said switch and support will be tilted as the cam engages the projection, means to move said lever around its pivot to vary the relation between said cam and projection and a scale cooperating with said moving means. 20

4. In an interrupter the combination with a rockable support, a mercury switch mounted thereon, means to bias said support in one direction, a projection on said support, a continuously rotatable cam adapted to engage said projection 25 and thereby tilt it against said bias, and means to adjust said cam from a position in which it engages said projection during its entire revolution to a position in which it fails entirely to engage said projection. 30

5. In an interrupter, a lever pivoted about an axis, a cam rotatably mounted on said lever, a support also pivoted about said axis and having a projection thereon adapted to be engaged by said cam, means to adjust said lever around said 35 axis relative to said support to thereby change the relative positions of said cam and said projection and power operated means to rotate said cam.

6. In an interrupter the combination of a switch adapted to be intermittently operated, an actuating member for said switch, means to move said actuating member through a path to operate said switch comprising a constantly rotating cam adapted to engage said member and thereby 45 move said member, a pivoted lever upon which said cam is supported, and means to move said lever around said pivot to shift said cam with respect to said member whereby said cam will engage said member a longer or shorter time during 50 each revolution.

7. In an interrupter, a switch, a lever pivoted about an axis, a cam rotatably mounted on said lever, a switch actuating member also pivoted about said axis and adapted to be engaged by said 55 cam, means to adjust said lever around said axis relative to said actuating member to thereby change the relative positions of said cam and said member and power operated means to rotate said cam. 60
